Morsell & Keeney
ATTORNEY.

UNITED STATES PATENT OFFICE.

CHARLES M. MARKHAM, OF MILWAUKEE, WISCONSIN.

CONCRETE SALVAGE JACK-HEAD.

1,374,598.

Specification of Letters Patent. Patented Apr. 12, 1921.

Application filed November 15, 1919. Serial No. 338,411.

To all whom it may concern:

Be it known that I, CHARLES M. MARKHAM, a citizen of the United States, and resident of Milwaukee, in the county of Milwaukee and State of Wisconsin, have invented new and useful Improvements in Concrete Salvage Jack-Heads, of which the following is a description, reference being had to the accompanying drawings, which 10 are a part of this specification.

This invention relates to improvements in concrete salvage jack heads adapted for supporting concrete work during construction and designed to permit the early release of 15 all form lumber.

It is one of the objects of the present invention to provide a mechanism for concrete construction which is adapted for jacking up and supporting beams, girders, floor 20 plates, concrete forms, machinery, decking, etc.

A further object of the invention is to provide a salvage jack head which has a positive means for clamping the lifting 25 member.

A further object of the invention is to provide a salvage jack head having a key and slot connection between the head member and the other parts in order to hold the head 30 member in any desired fixed position.

A further object of the invention is to provide a salvage jack head in which the desired vertical adjustment may be quickly attained or the parts released for removal 35 from the completed structure, and furthermore, that the parts of the jack may be easily separated for convenience in packing.

A further object of the invention is to provide a salvage jack head in which the head 40 may be disengaged from the work in order to permit the form lumber to be released for re-use immediately after the concrete has set.

A further object of the invention is to 45 provide a salvage jack head which is of simple construction, is strong and durable and is well adapted for the purpose desired.

With the above and other objects in view, 50 the invention consists of the improved concrete salvage jack head and its parts and combinations as set forth in the claims, and all equivalents thereof.

In the accompanying drawing in which the same reference characters indicate the 55 same parts in all of the views:

Figure 1 is a front view of the improved concrete salvage jack head showing the method of supporting joists and concrete 60 flooring;

Fig. 2 is an enlarged detailed view showing the arrangement of the key; part of the head being shown in section; and

Fig. 3 is a vertical sectional view of the flanged cap showing manner of connecting 65 an upper additional movable tubular member to the lower member.

Referring to the drawing, the numeral 5 indicates a tubular standard which has any 70 convenient or suitable form of base, (not shown). Slidably connected to the tubular standard 5 near its upper extremity, is

a jack head member 6 which engages joists 7 used in supporting beams 8 and the concrete flooring support 9. To provide a 75

means of connection between the tubular standard 5 and similar standards to be used on the floor above, the upper extremity of 80

said tubular standard 5 is partially threaded into a flanged cap 10 and the flanged cap 10 is provided with a flat surface 11 upon which the flat surface of a similar flanged cap 12 rests. Through the flanged cap 12 and into 85

the lower flanged cap 10 until it meets tubular standard 5 is threaded an additional tubular standard 5'. In this manner the bases of additional tubular standards for 90

use on upper floors are firmly secured. The jack head member 6 is composed of a flat base 13 and two upwardly projecting arms 14 which give it a channel shape in cross-section for receiving the joists 7. Attached 95

to said jack head member 6 by means of a cord or chain 15 is a wedge-shaped key 16. This key 16 has one horizontal edge 17 upon which the base of the head member 6 100

rests and an angularly inclined edge 18, thus giving the wedge-shaped key 16 a tapering shape. Said key 16 adjustably fits into a horizontal slot 19 provided in 105

said tubular standard member 5 near its upper extremity and by tapping the key into or out of the slot, the head may be raised or lowered as desired. The cord or chain 15 prevents the accidental loss of the 105 wedge member.

In operation, the joist 7 is fitted into the channel shaped head 6 and the key 16 is tapped into the slot 19 until the head 6 is raised to the desired position and the joist 5 7 firmly secured. After the concrete, which is being supported by the joist 7, beams 8 and flooring 9, has set, the key 16 is tapped out of the slot 19 allowing the head 6 to be lowered, thereby releasing the joists 7 and 10 permitting their use elsewhere.

From the foregoing description, it will be seen that the concrete salvage jack head is of very simple construction and is well adapted for the purpose described.

15 What I claim as my invention is:

1. A concrete salvage jack head, comprising a tubular standard having a slot, a wedge shaped key reposed in said slot and having a horizontal edge and an angularly 20 inclined edge, a head member of channel shape in cross-section carried on and through which said tubular standard extends and projects above, said head member resting on the horizontal edge of said 25 key, and a means for connecting additional

tubular standard members to the upper extremity of said tubular standard.

2. A concrete salvage jack head, comprising a standard having a slot, a wedge shaped key reposed in said slot, a head member having two upwardly projecting arms and a flat base of greater width than the standard to form a channel shaped recess, to support a timber on each side of the standard, said standard extending through 30 the head member, said head member being carried on said standard member and resting on said key, and a means for connecting additional standard members to the upper extremity of said standard. 35

3. A concrete salvage jack head, comprising a standard having a slot, a wedge shaped key entering said slot, a head member carried on said tubular standard member and resting on said key, and a pair of threaded flanged caps for connecting additional standard members to the upper extremity of 40 said standard. 45

In testimony whereof I affix my signature.
CHARLES M. MARKHAM.
